(57) CLAIM

The ornamental design for a game piece, as shown and described.

DESCRIPTION

FIG. 1 is a rear perspective view of the game piece, showing our new design;

FIG. 2 is a top plan view of the game piece;

FIG. 3 is a bottom plan view of the game piece;

FIG. 4 is a left side view of the game piece;

FIG. 5 is a right side view of the game piece;

FIG. 6 is a front plan view of the game piece, which is a mirror image of the rear plan view thereof; and,

FIG. 7 is the rear plan view of the game piece.

The broken lines in the drawings illustrate portions of the game piece that form no part of the claimed design.
